(57) **CLAIM**

The ornamental design for a combination pacifier and teether with foldable handle, as shown and described.

DESCRIPTION

FIG. 1 is a top plan view of a combination pacifier and teether with foldable handle, showing my new design with the teether handle in a folded position,

FIG. 2 is a side perspective view of the same, with the teether handle in an unfolded position,

FIG. 3 is a top view thereof; and,

FIG. 4 is a perspective view thereof.

The broken lines in the drawings depict portions of the combination pacifier and teether with foldable handle that form no part of the claimed design.

1 Claim, 4 Drawing Sheets
